(57) **CLAIM**

(52) **U.S. Cl.**

The ornamental design for a cosmetic apparatus for massaging anticellulite and antiwrinkle treatment as shown and described.

USPC **D24/200**

DESCRIPTION

(58) **Field of Classification Search**

FIGURE 1.1 is a front elevation view of the cosmetic apparatus for massaging, anti-cellulite, and anti-wrinkle treatment, according to my design.

USPC D24/185–190, 200, 127, 130, 133,
D24/145–147, 155–156, 158, 183,
D24/206–208, 214–215, 231, 234;
D8/391, 387; D23/303, 318, 322;
D13/168; D14/218

FIGURE 1.2 is a left side elevation view thereof.

CPC .. A61M 25/065; A61M 5/42; A61M 25/0612;
A61M 25/00; A61M 39/00; A61M 27/00;
A61M 25/0043; A61M 25/0067; A61M
25/0097; A61F 2/958; A61F 13/02; A61F
2013/00885; A61F 7/02; A61F 7/034;

FIGURE 1.3 is a partial back elevation view thereof.

FIGURE 1.4 is a partial enlarged perspective view thereof.

FIGURE 1.5 is a partial enlarged front elevation view thereof.

The broken lines in the figures illustrate the portions of the cosmetic apparatus for massaging, anti-cellulite, and anti-wrinkle treatment that form no part of the claimed design.
